UNITED STATES PATENT OFFICE.

LOUIS A. MAXSON, OF CLAREMONT, NEW HAMPSHIRE, ASSIGNOR TO SULLIVAN MACHINERY COMPANY, A CORPORATION OF MASSACHUSETTS.

FEEDING MECHANISM.

Application filed February 1, 1922. Serial No. 533,411.

My invention relates to feeding mechanisms, and more particularly to feeding mechanisms for use in connection with rock drilling devices.

5 An object of my invention is to provide an improved feeding means. Another object of my invention is to provide an improved feeding mechanism by the use of which a rapid feeding movement in one direction and slow feeding movement in the opposite direction may be readily obtained, the change from rapid to slow feed being automatically accomplished and the sole care of the drill runner or tool operator being 10 15 20 25 30 35 40 45 50 55 60 65 70 75 80 85 90 95 turned by the operator in a clockwise direction. This will result in a counter-clockwise rotation of the shaft 27 and so of the pinion 29 and gear 30. The pinion 29 which 5 intermeshes with the gear 18 will cause the latter to rotate in a clockwise direction and the pawls 19 will cause the sleeve 16 also to rotate in a clockwise direction and so the feed screw, which is free to rotate in a 10 clockwise direction as previously described, will be so rotated. The gear 30 rotating in a counter-clockwise direction will rotate the nut 22 in a clockwise direction, but the angular speed of rotation of the nut is greater 15 than the angular speed of rotation of the feed screw 5 by reason of the tooth ratios of the several gears employed. Accordingly, the tool 1 will be fed forward at a speed much less than would result from the speed 20 of rotation of the nut 22 if the feed screw remained stationary, and thereby a relatively slow and easy forward feed will be provided.

When the handle 33 is turned in a counter-clockwise direction, the shaft 27 will be turned clockwise and so will the pinion 29 and gear 30. The pinion 29 will then turn the gear 18 in a counter-clockwise direction and the pawls will slip over the teeth on the 25 ratchet upon the sleeve 16, this being assured by reason of the fact that the feed screw is prevented from counter-clockwise rotation by the pawls 11 and the ratchet 12. The feed screw will therefore remain stationary. The gear 30 will drive the nut 22 and accordingly the retractive movement of the tool 1 will be equivalent to the full speed that would be accomplished by the use of 30 the nut upon the feed screw. It will therefore be evident that the tool may be rapidly retracted and slowly fed forward as may be desired, the change in the rate of feed being automatically accomplished by the mechanism disclosed.

While I have in this application specifically described one form which my invention may assume in practice, it will be understood that this form of the same is shown for purposes of illustration and 45 that the invention may be modified and embodied in various other forms without departing from its spirit or the scope of the appended claims.

What I claim as new and desire to secure 50 by Letters Patent is:

1. In a rock drilling mechanism, a drilling tool, and feeding means therefor including a reversely rotatable operating member, said feeding means including means always 55 automatically operative to provide different rates of feed upon rotation of said member in opposite directions at substantially equiangular speeds.

2. In a rock drilling mechanism, a drilling 60 motor, and reversible mechanical feed-

ing means therefor including a reversely rotatable operating member, said feeding means including means always automatically operative to provide different rates of feed upon rotation of said member in 70 opposite directions at substantially equiangular speeds.

3. In a rock drilling mechanism, a drilling 75 motor, and reversible feeding means therefor including a reversely rotatable operating member and a cooperating feed screw operatively connected to said motor, said feeding means including means always automatically operative to provide different rates of feed upon rotation of said member 80 in opposite directions at substantially equiangular speeds.

4. In a rock drilling mechanism, a drilling 85 motor, and reversible feeding means therefor including a reversely rotatable operating member, said feeding means including means always automatically operative to provide a slow forward and a rapid reverse feed upon rotation of said member 90 in opposite directions at substantially equiangular speeds.

5. In a rock drilling mechanism, a drilling 95 motor, and reversible feeding means therefor including a reversely rotatable operating member and a rotatable feed screw operatively connected to said motor, and means to prevent rotation of said feed screw in one direction, said feeding means including means always automatically operative to provide different rates of feed in 100 opposite directions upon rotation of said member in opposite directions at substantially equiangular speeds.

6. In a rock drilling mechanism, a drilling 105 motor, and reversible feeding means therefor including a reversely rotatable operating member, a rotatable feed screw operatively connected to said motor, and means to prevent rotation of said feed screw in one direction, said feeding means including means always automatically operative to provide a slow forward and a rapid reverse feed upon rotation of said member 110 in opposite directions at substantially equiangular speeds.

7. In a rock drilling mechanism, a drilling 115 motor, and reversible feeding means therefor including a reversely rotatable operating member, a rotatable feed screw operatively connected to said motor, and means for positively preventing rotation of 120 said feed screw in one direction, said feeding means including means always automatically operative to provide a slow feed in one direction and a rapid feed in the 125 opposite direction upon rotation of said member in opposite directions at substantially equiangular speeds.

8. In a rock drilling mechanism, a drilling 130 motor, and reversible feeding means therefor

including a reversely rotatable operating member, said feeding means including means always automatically operative to provide fast and slow feeding speeds upon rotation 5 of said member in opposite directions at a substantially uniform angular speed.

9. In a rock drilling mechanism, a drilling motor, and reversible feeding means therefor including a reversely rotatable feed nut and 10 a cooperating feed screw operatively connected to said motor, said feeding means including means always automatically operative to provide different rates of feed upon rotation of said feed nut in opposite 15 directions at substantially equiangular speeds.

10. In a rock drilling mechanism, a drilling motor, and reversible feeding means therefor comprising a feed screw operatively 20 connected to said motor, a reversely rotatable member surrounding said feed screw and rotatable relative thereto in one direction and rotatable therewith in the other direction, and pawl and ratchet mechanism 25 associated with said feed screw and member, said feeding means including means always automatically operative to provide different rates of feed in opposite directions upon rotation of said member in opposite directions 30 at substantially equiangular speeds.

11. In a rock drilling mechanism, a drilling motor, and reversible feeding means therefor comprising a reversely rotatable operating member, a feed nut carried by said 35 motor and movable therewith, a feed screw operatively connected to said nut, and means always automatically operative for effecting a slow relative rotation between said nut and screw in one direction or a rapid relative 40 rotation therebetween in the opposite direction upon rotation of said member in opposite directions at substantially equi-angular speeds.

12. In a rock drilling mechanism, a drilling motor, and reversible feeding means therefor comprising a rotatable feed screw, a feed nut operatively connected to said motor and cooperating with said feed screw, and means for effecting simultaneous differential rotation of said nut and screw during forward feed and rotation of said nut while said screw is positively held stationary during reverse feed.

13. In a rock drilling mechanism, a drilling motor, and reversible feeding means therefor comprising a rotatable feed screw, a feed nut operatively connected to said motor and cooperating with said feed screw,

and means always automatically operative to effect slow relative rotation between said 60 nut and screw during the feed in one direction and rapid relative rotation therebetween during feed in the opposite direction.

14. In a rock drilling mechanism, a drilling motor, and reversible feeding means 65 therefor comprising a rotatable feed screw, means for positively preventing rotation of said screw in one direction, a feed nut operatively connected to said motor and cooperating with said feed screw, said feed nut 70 being rotatable on said screw, a member having a connection with said screw preventing relative rotation but permitting relative longitudinal movement, and a member rotatable relative to said other member during rotation of said nut in one direction and adapted to be fixed relative thereto during opposite rotation of said nut.

15. In a rock drilling mechanism, a drilling motor, and reversible feeding means 80 therefor comprising a rotatable feed screw, means for positively preventing rotation of said screw in one direction, a feed nut operatively connected to said motor and cooperating with said feed screw, said nut being 85 rotatable on said screw, a member having a connection with said screw preventing relative rotation but permitting relative longitudinal movement, a member rotatable relative to said other member during 90 rotation of said nut in one direction and adapted to be fixed relative thereto during opposite rotation of said nut, and means for actuating said members and feed nut comprising a plurality of pairs of meshing gears. 95

16. In a rock drilling mechanism, a drilling motor, and feeding means therefor comprising a feed screw operatively connected to said motor, and a cooperating reversely rotatable operating element surrounding said 100 feed screw and adapted to rotate with the same when rotated in one direction or rotate relative thereto when rotated in an opposite direction.

17. In a rock drilling mechanism, a drilling motor, and feeding means therefor comprising a feed screw operatively connected to said motor, and a cooperating reversely rotatable operating element surrounding said feed screw and rotatable relative thereto 110 when rotated in one direction and rotatable therewith at the same angular rate therewith when rotated in the other direction.

In testimony whereof I affix my signature.

LOUIS A. MAXSON.
